UNITED STATES PATENT OFFICE

SAMUEL RUSSELL CARPENTER, OF SWEETWATER, TEXAS

CAKE KNOCKER FOR OIL PRESSES

Application filed July 1, 1929. Serial No. 375,095.

The present invention relates to cake knocker for oil presses and has as its primary object the provision of means for knocking the cakes from the boxes of an oil press by mechanism operable through the oil pressure systems of the press.

Another very important object of the invention resides in the provision of a mechanism of this character which is simple in construction, inexpensive to manufacture, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

20 In the drawings:

Figure 1 is a side elevation of an oil press of my improved mechanism associated therewith.

Figure 2 is a vertical section through the mechanism embodying the features of my invention.

Figure 3 is a vertical section through one of the boxes showing an extractor finger entering the same.

30 Figure 4 is an enlarged detail section taken substantially on line 4—4 of Figure 2.

Figure 5 is a fragmentary top plan view of the rail and supporting bars.

Figure 6 is a sectional view taken substantially on the line 6—6 of Figure 2.

Figure 7 is a sectional view taken substantially on line 7—7 of Figure 2.

Figure 8 is a side view partly in section and partly in elevation of a valve and automatic control means therefor embodying a part of this invention.

Figure 9 is a top plan view of the structure as illustrated in Figure 8.

Figure 10 is a transverse horizontal section 45 taken through the valve.

Referring to the drawings in detail it will be seen that the numeral 5 denotes a well known type of oil press which includes a plurality of boxes 6 in which is formed cakes 50 7 after the oil has been pressed therefrom.

My improved apparatus consists of a rail 8 fixed to the top of the press and extending laterally and horizontally therefrom and having a channel iron fixed to the extremity thereof and depending downwardly therefrom and fixed in a frame 10 projecting laterally and horizontally from the bottom portion of the press.

A casing C is mounted over these parts 8, 9 and 10, and that side of the casing adjacent the press is open for the full length of said casing. An I-beam 14 depends from a hanger 15 having a roller 16 journaled therein and ridable on the upper surface of the I-beam 8. A plurality of extractor fingers 17 are fixed to the depending beam 14 and projects through the open side of the casing, said fingers having depending extensions 19 on their outer extremities to engage the cake 7 as shown to advantage in Figure 3.

Springs 21 have each one end thereof anchored to the beam 14, the opposite end portions of the springs adapted to extend through openings 30 formed in the wall 26 of the casing C to be anchored to the opposite ends of a bracket member 28 clamped as at 29 to a cylinder 25.

As illustrated to advantage in Figures 1 and 2 this cylinder 25 projects through an opening in the wall 26 of the casing C and through an opening in the intermediate portion of the channel bar 9. Furthermore the cylinder 25 may be made of heavy piping, and is closed at its outer end with a screw threaded cap 25'. A cylinder block 27 is fastened to the channel bar 9 and threadedly engaged with the cylinder 25, as shown. A plunger rod 22 is slidable in the cylinder 25 and cylinder blocks 27, the said rod 22 projecting outwardly of the said cylinder block 27 and having its outer end fixed as at 22 to an intermediate portion of the beam 14.

A valve 31 is disposed within the casing C and a conduit 32 leading from a suitable source of oil supply is incorporated with the valve 31 in registry with the inlet opening 32' formed in the valve. The valve 31 is further provided with an outlet opening 33' from which a conduit 33 leads to be associated with the port 27' in the cylinder block 27,

said conduit 33 being incorporated therewith through the medium of a suitable connection 34. Diametrically opposite to the outlet opening 33' the valve is provided with an exhaust port 35' from which leads the exhaust pipe 35. The hollow valve core designated generally by the reference character 36, and located within the casing is provided with the port 37, 38 and 39, respectively. Thus it 10 will be seen that oil under pressure from the conduit 32 will enter the valve 31 when the ports 37, and 38, respectively are in registry with the ports 32' and 33' whereby the oil received into the valve casing will be conducted through the conduit 33 into the cylinder block 27, to flow through the cylinder 25 for exerting pressure upon the rod 22, causing the rod 22 to push the beam 14 so as to 15 push the finger 17 which in turn will push the cakes from the boxes. Under normal conditions of course it will be appreciated that the springs 21, and when the oil pressure is released by the valve 31 in an automatic manner to be hereinafter described will 20 cause the retraction of the fingers, the beam 14 being drawn back by the spring until said beam will almost touch the cylinder block. 25 To automatically control the valve 31 during the operation of the press, there is provided an elongated rod 39, pivoted intermediate its ends to the frame 10 as at 39'. As 30 illustrated one end of this rod 39 is disposed beneath the reciprocating portion of the press for contact with the said sliding portion 35 of the press during the operation of the same. At its opposite end the rod 39 has a pivotal connection 41 with a substantially vertically disposed rod 40. Adjacent its upper end and upon the inner face thereof, 40 the rod 40 has adjustably mounted thereon a block 42, the upper edge of which block is beveled as at 42'. The block 42 is provided with a slot 43, and a screw or bolt 44 extends laterally from the rod 40 and through said 45 slot, the said screw 44 having a locking nut 45 threadedly engaged therewith and contacting with the block 42 so that the block may be maintained in an adjusted position longitudinally with respect to the rod 40. 50 Located within the casing C and adjacent the upper end of the rod 40, there is provided a suitable bracket 48. As illustrated, this bracket is somewhat T-shaped in formation, and has a downwardly depending lateral arm 55 47 to one end of which a spring 46 is anchored, said spring at its opposite end being fixed to the inner end of the screw 44 for urging the rod 40 inwardly in contacting relation at its upper edge with a roller 49 rotatably 50 supported on the body portion of the bracket 48, as at 50. A lock 52 is pivoted intermediate its ends as at 52' to the upstanding laterally extending arm 51 of the said bracket, and it will be noted that the inner end portion 65 of the latch 52 is adapted to normally

rest between the flanges of the roller 49 as illustrated. At its opposite end the latch 52 is suitably notched as at 53 for a purpose which will presently present itself.

The valve 31 is provided with a suitable operating member 54, said handle comprising an elongated straight portion 55, and at its opposite end being curved as at 56. The handle of course is associated with the valve stem exteriorly of the upper end of the valve 75 casing.

In Figures 9 and 10 are shown the positions of the valve and handle when the boxes 6 of the press have been moved upwardly for forcing the oil out of the cakes 7. In this connection it will be noted that the handle has its straight end 55 engageable with the notch in the latch 52, said latch being in a substantially horizontal position and having its inner end resting upon the roller 49, as shown 85 to advantage in Figure 8. A coil spring 61 is suitably anchored within the casing and is fixed to the handle 54 adjacent its curved portion 56 for maintaining the handle in engagement with the latch 52. When in this position it will be seen that the ports 37 and 39 are in registry with the outlet port 33' and exhaust port 35' respectively, so that the oil may be exhausted from the cylinder 25 for 95 permitting a downward movement of the boxes 6, after the cakes 7 have been pushed therefrom and the press begins its downward return movement.

A horizontal bar 57 has one end thereof fixed to the beam 14, as shown in dotted lines in Figure 1, and this bar projects laterally from said beam. Slidably disposed upon the outer end of the bar 57 is a sleeve 58 which is provided with a detent 59. A spring 60 is coiled about the outer extremity of the rod 57 and has one end thereof anchored to the rod, the opposite end of the spring being fixed to an adjacent end of the sleeve 58 acting as a cushioning means for the sleeve. 100

Therefore it will be seen that during the 110 exhaust of the oil from the cylinder 25 the plunger 22 is forced inwardly of the cylinder upon its return stroke, the springs 21 exerting pressure upon the beam 14 as is obvious.

As the oil is exhausted from the cylinder 115 25 it is apparent that the lower end of the movable portion of the press upon its downward stroke will engage with the adjacent end of the bar 39 rocking the same upon the pivot 39', thus forcing the bar 40 upwardly, 120 whereby the upper end of the bar will engage with the adjacent inner end of the latch 52, thus rocking said latch upon its pivotal connection and consequently releasing the actuating member 54 of the valve whereby the 125 ports 37 and 38 will register with the ports 33' and 32' respectively, thus permitting the inflowing oil to find its way into the cylinder block 27 and cylinder 25 to push the beam 14 forwardly whereby the fingers 19 may en- 130

gage with the cakes 7 as have previously been described. Apparently then the beam 14 being pushed by the rod will of course carry the bar 57 inwardly during the movement of the beam so that the detent 59 of the sleeve 58 will engage with the rounded extremity 53 of the valve operating member 54 for returning the member to that position shown in full line in Figure 9 and against the action of the spring 61 so that when the beam 14 is substantially at the completion of its inward movement the ports 37 and 39 will again register with the ports 33' and 35' respectively to permit an exhaust of the oil to permit the return of the beam 14 for retracting the finger.

From a study of Figure 8 it will be apparent that when the rod 40 has been moved upwardly for engagement with the latch 52 for releasing the operating member 54, the said rod 40 will continue upwardly and be forced outwardly and out of contact with the latch 52 since obviously the block 42 will interpose between the roller 50 and the said rod 40 for urging the same to that position shown in dotted lines in the figure. This of course will permit the latch 52 to return to its position upon the roller 50 by gravity so as to be in engageable position when the operating member 54 is moved for engagement with the latch for contact with the detent 59 upon the return of the beam 14 and rod 57 as is apparent.

It will be seen that this apparatus is exceedingly simple in its construction, inexpensive to install, and thoroughly efficient and reliable in use. The present embodiment of the invention, however, has been disclosed in considerable detail merely for the purpose of exemplification, since in actual practice it attains the features of advantage enumerated as desirable in the statement of the invention and the above description.

It will be apparent that changes in the details of construction, and in the combination and arrangement of parts may be resorted to without departing from the spirit or scope of the appended claims.

Having thus described the invention, what I claim as new and desire to secure by Letters Patent is:—

1. A device for pushing cakes from the boxes of an oil press, and comprising a plurality of fingers, one for each box, a vertical beam to which one end of the fingers are attached, said fingers at their opposite ends respectively provided with a depending extension for engagement with a cake in one box, and means for actuating the beam to push the fingers for extracting the cakes from the boxes.

2. A device for pushing cakes from the boxes of an oil press, and comprising a plurality of fingers, one for each box, a vertical beam to which one end of the fingers are at-

tached, said fingers at their opposite ends respectively provided with a depending extension for engagement with a cake in one box, and means for actuating the beam to push the fingers for extracting the cakes from the boxes, means associated with the beam for normally holding the fingers retracted out of the boxes, a rod attached to the beam, a cylinder, a conduit leading to the cylinder whereby oil from the presser may be fed to the cylinder for actuating the rod for moving said beam toward and away from the press for moving the fingers into and out of the boxes.

3. A device for pushing cakes from the boxes of an oil press, and comprising a plurality of fingers, one for each box, a vertical beam to which one end of the fingers are attached, said fingers at their opposite ends respectively provided with a depending extension for engagement with a cake in one box, and means for actuating the beam to push the fingers for extracting the cakes from the boxes, means associated with the beam for normally holding the fingers retracted out of the boxes, a rod attached to the beam, a cylinder, a conduit leading to the cylinder whereby oil from the presser may be fed to the cylinder for actuating the rod for moving said beam toward and away from the press for moving the fingers into and out of the boxes, a horizontal rail, a hanger having a roller therein ridable on the rail, said hanger being attached to the upper end of the beam.

4. A device for extracting cakes from the boxes of an oil press, comprising a vertically suspended beam adapted for movement on a horizontal plane, means for movably supporting said beam, a plurality of ejector fingers projecting laterally from the beam, there being one finger for each of the boxes of the oil press, means associated with the beam for normally holding the fingers retracted out of the boxes, a rod attached to the beam, a cylinder, a conduit leading to the cylinder whereby oil from the press may be fed to the cylinder for actuating the rod thereby moving the beam toward or away from the press for moving the fingers on a horizontal plane into and out of the boxes, a valve structure in said conduit, and means operatively connected with said vertical beam and arranged in the path of movement of a part of the press for operating the valve to control the supply of oil to the cylinder.

5. A device for extracting cakes from the boxes of an oil press, said means comprising a horizontally movable vertically disposed beam, means for suspending said beam vertically, said means including a horizontally disposed rail, a hanger on the upper end of the beam, a roller in the hanger ridable on the rail, valve controlled fluid means for actuating said beam, and a plurality of fingers

arranged in vertical spaced alinement projecting from one side of the beam, there being one finger for each of the boxes of the oil press.

- 5 6. A device for extracting cakes from the boxes of an oil press, said means comprising a vertically movable beam, means for movably supporting said beam, fingers projecting from one side of the beam, there being 10 one finger for each box of the oil press, said fingers at their free ends terminating in downwardly depending cake engaging terminals, a rod attached to the beam, a cylinder slidably accommodating said rod, a conduit 15 leading to the cylinder whereby oil under pressure from the press may be fed to said cylinder for operating said rod, a valve arranged in said conduit, a latch member extending from said beam and having means 20 thereon adapted for cooperation with an operating handle of the valve for moving said valve to an exhausting position upon return movement of the beam, said latch adapted to engage the operating handle of the valve 25 when the same is in exhausting position, and means for actuating the latch to permit release of the valve upon a return stroke of the oil press.

7. A device for extracting cakes from the 30 boxes of an oil press, said means comprising a vertically movable beam, means for movably supporting said beam, fingers projecting from one side of the beam, there being one finger for each box of the oil press, said 35 fingers at their free ends terminating in downwardly depending cake engaging terminals, a rod attached to the beam, a cylinder slidably accommodating said rod, a conduit leading to the cylinder whereby oil under 40 pressure from the press may be fed to said cylinder for operating said rod, a valve arranged in said conduit, a latch member extending from said beam and having means thereon adapted for cooperation with an operating 45 handle of the valve for moving said valve to an exhausting position upon return movement of the beam, said latch adapted to engage the operating handle of the valve when the same is in exhausting position, and 50 means for actuating the latch to permit release of the valve upon a return stroke of the oil press, including means operatively associated with the oil press so that upon said return stroke of the oil press oil is forced into 55 the cylinder for actuating the plunger.

8. A device for extracting cakes from the boxes of an oil press, comprising in combination a movable member, means for utilizing oil under pressure from the oil press for 60 actuating said movable member, said means including a valve controlled conduit, latch means co-operable with the valve for moving the latter to an exhausting position upon movement of said movable member in one direction, and means controlled by the move- 65

ment of the press for releasing said latch means whereby said valve is actuated for directing oil under pressure through said conduit for effecting an operation of said movable member.

In testimony whereof I affix my signature. 70
